UNITED STATES PATENT OFFICE.

AUGUSTUS F. THOMPSON, OF HUNTINGTON, WEST VIRGINIA.

GAS-BURNER.

1,381,030.

Specification of Letters Patent. Patented June 7, 1921.

Application filed September 27, 1920. Serial No. 412,941.

To all whom it may concern:

Be it known that I, AUGUSTUS F. THOMPSON, a citizen of the United States of America, and a resident of Huntington, county 5 of Cabell, and State of West Virginia, have invented certain new and useful Improvements in Gas-Burners, of which the following is a full and clear specification.

This invention relates to burners for use 10 in gas-burning grates, heating and cooking stoves and any other apparatus, and the object of this invention, generally stated, is to so construct the burners as to permit perfect combustion and to eliminate all noise 15 and odor, as more fully hereinafter set forth.

In the drawing,—

Figure 1 is a perspective view partly broken away of a preferred form of my apparatus;

20 Fig. 2 is a perspective view of another form.

My present invention has relation particularly to that type of gas-burner covered by my former Patent No. 909,711, dated January 25 12, 1909.

In its preferred form, my device consists of a gas-supply pipe 1, rising from which is a series of Bunsen type of mixer tubes 2, properly spaced along the supply pipe 30 and having their upward ends open and provided with air-ingress openings 3. Affixed to the upper ends of these mixing tubes is a long metallic chamber 4 closed on all sides and at its ends. The upper ends of 35 the mixing tubes communicate with the interior of this chamber 4. The only outlets this chamber 4 is provided with is a series of sets of circular holes 5 formed in the upper wall of the chamber, these circular sets 40 of holes being staggered with reference to the mixer tubes 2. As will be obvious, all of the tubes 2 discharge their contents into the box or chamber 4, and the gas and air are further mingled in this box, after which 45 they make their exit up through the holes 5.

Extending up through the chamber 4 is a series of tubes 6, one being provided for each set of holes 5 and being arranged in the center thereof. These tubes are open at 50 both their upper and lower ends and therefore obviously form air passages, up through which air passes to thus supply air continuously into the center of each tubular flame formed by the circular burner-openings 5. 55 It will thus be observed that I not only provide for a preliminary mixing of the air and gas in the tubes 2 and a distribution of

this mixed air and gas at different points along the chamber 4, but I also provide for again and more thoroughly mixing air and 60 gas in the chamber 4, it being obvious that this additional mixing of the air and gas is promoted by locating the sets of burner-openings 5 out of alinement with the mixing tubes. In addition to thus a second 65 time and more thoroughly mixing the air and gas in box 4, I provide each flame with an ample supply of oxygen by means of the tubes 6, this additional supply of oxygen to each flame being delivered into the center 70 of the flame. In this way, as is obvious, I provide for perfect combustion of the gas, and practical experience with this type of burner has proven that the burner operates entirely without any noise as well as 75 without odor, and, further, that by supplying air into the center of each flame under atmospheric pressure only I do away with the objection of having the flame leaping away from the burner. 80

The above results are obtained with the form of burner shown in Fig. 2, in which the supplemental mixing chamber 4 is made circular in shape.

The nature and scope of the invention 85 having been thus indicated and its preferred embodiment having been specifically described, what is claimed as new is:

A gas burner comprising a horizontally-disposed and closed mixing-chamber provided at intervals in its top-wall with a series of sets of jet perforations, a plurality of mixing-tubes discharging into and through the bottom-wall of said mixing-chamber at points staggered with relation to 90 the sets of jet perforations, each of said mixing-tubes being provided with one or more air-intake-openings, a gas-supply-pipe connected successively to the lower ends of the mixing-tubes below the air-intake-openings, and a series of air-supply tubes each 95 being mounted in the top and bottom walls of the mixing-chamber and arranged concentrically with a set of the perforations and open only at its ends to supply air from beneath the mixing-chamber to the middle 100 of each set of jet perforations. 105

In testimony whereof I hereunto affix my signature.

AUGUSTUS F. THOMPSON.
